UNITED STATES PATENT OFFICE.

GEORGE GORDON BOWER, OF BAINBRIDGE, GEORGIA.

INTERNAL-COMBUSTION ENGINE.

1,263,736.

Specification of Letters Patent. Patented Apr. 23, 1918.

Application filed April 20, 1917. Serial No. 163,330.

To all whom it may concern:

Be it known that I, GEORGE GORDON BOWER, a citizen of the United States, residing at Bainbridge, in the county of Decatur and State of Georgia, have invented certain new and useful Improvements in Internal-Combustion Engines, of which the following is a specification, reference being had therein to the accompanying drawing.

10 This invention relates to improvements in internal combustion turbines, one object of the invention being the provision of a mechanism which combines a turbine adapted to be operated by the impulse from the exhaust of the exploded charge and also the expansion thereof and which in turn operates the compressor mechanism so that the gas charge is drawn within its respective cylinders compressed and exploded to be 15 directed to the active surfaces of the stator and rotor of the turbine.

A further object of this invention is the provision of means whereby the speed of the compressor may be regulated relative 20 to that of the rotor of the turbine or if preferable the gas may be compressed by the exploder discharged therefrom through the discharge ports through the conduits to the annular chamber of the turbine and there 25 exploded or burned.

A still further object of the invention is the provision of manually controlled mechanism whereby the degree of compression within the cylinder may be changed at will.

30 A still further object of this invention is the provision of a mechanism by means of which each cylinder of the rotor of the exploder is scavenged so that the maximum efficiency may be obtained from the explosion of the compressed charge for delivery to the turbine.

A still further object of this invention is the provision of a novel method of cooling the rotating parts of the present apparatus 45 so that the apparatus will operate to its maximum efficiency.

A still further object of this invention is its capacity to draw in and compress the gas in its cylinders to discharge the same therefrom through the discharge ports into the conduits to the annular chamber of the turbine, and exploding or burning said compressed gas in said annular chamber, or ex-

ploding or burning it in the conduits before reaching said annular chamber.

55

In the accompanying drawings:

Figure 1 is a vertical sectional view through the exploder and the inlet end of the turbine.

Fig. 2 is a section taken on line 2—2 of Fig. 1.

Fig. 3 is a section taken on line 3—3 of Fig. 1.

Fig. 4 is a section taken on line 4—4 of Fig. 1.

Fig. 5 is an elevation of the turbine taken from the compressor end thereof.

Fig. 6 is a detail view showing the position of the cylinders of the compressor.

Figs. 7 and 8 are detail views of the connecting rod.

Referring to the drawings, the numeral 10 designates the stator of the turbine which is of any well known construction, such as Parsons, Curtiss, Rateau or De Lavel, or in fact 75 any construction of turbine that will prove efficient with the present combination.

This is connected through means of the conduits 11 to the stationary annular member 12 of the compressor 13, while mounted 80 for rotation within this is the rotor 14 provided with the radial cylinders 15, this rotor being shown as constructed of two members 16 and 17, and having respectively four cylinders to each member, although it is possible to use two cylinders to each member, or four in all.

Mounted for slight oscillatory movement concentrically of the sleeve 18 of the rotor, is a crank shaft 19 whose adjustment is 90 changed by means of the lever and ratchet 20 so as to regulate the degree of compression of the respective pistons 21 which are connected through the connecting rods 22 to the respective cranks 23 and 24 of the crank 95 shaft. It will be noted that there are four connecting rods to each crank (as shown) and that each connecting rod is provided with the U-shaped connecting end 25 which fits astride one or the other so that the rotor 100 is permitted to rotate about its respective crank and consequently cause the pistons to be reciprocated two cycles each rotation of the rotor.

The stator of the compressor is composed 105 of two sections 26 and 27 which are pro-

- vided with the central circumferential recessed flange member 28 for the reception of the centrally disposed external rib or flange 29 of the rotor, this construction permitting the easy assembly of the rotor within the stator while the rib and its receptacle prevent the leakage of any of the charge from one side of the periphery of the stator to the other, there being provided circumferential packings 30 in the stator for engagement with the opposite sides of the rotor.
- The stator is further provided with two intake ports 31 which are in communication with the intake manifold 32 which in turn is supplied by the carburetor 33 while the conduits 11 are in communication with the exhaust ports 34 therein. It will be noted that the intake and exhaust ports of one of the members of the rotor are directly aligned with the intake and exhaust ports of the other member of the rotor so that a balanced action is secured and consequently two substantially constant streams of gas are sucked in and compressed at diametrically opposite points of the exploder simultaneously while two substantially constant streams of exhaust fluid from diametrically opposite points of the exploder are directed to the turbine, while between the points of intake and exhaust as before stated, the compressions of the gas are taking place simultaneously at diametrically opposite points of the exploder, the three strains or labors of the exploder all being respectively diametrically opposite from the main shaft, preserves a perfect balance of the exploder.

This device is so constructed that each piston receives a charge during 90° or more of the revolution of the rotor of the compressor exhausting for a similar period so that there is a possibility of action of 150° or more as may be desired.

In order to change the speed of the compressor relative to the turbine, there is interposed between the rotor of the turbine and the rotor of the stator, the transmission mechanism 35 being provided with the lever 36, so that the speed between these two members may be changed and the compressor may be retarded or accelerated relative to the rotor of the turbine.

It will be noted that the inner ends of the cylinders of the compressor are open through the cuff 18 and that the same are held in place at the inner ends by means of the bolts 37 while the outer cylinder 16 of the rotor receives the threaded end 39 of its cylinder so that the cylinder sits flush therein, each cylinder being insertible through the outer cylinder to the inner, as illustrated, and thus being readily assembled.

In order that the internal mechanism of the compressor may be properly cooled, air

is permitted to enter through the inner open ends of the cylinder due to the motion of the pistons but to assist in this, the fan 40 is employed.

In starting the present mechanism any form of hand or electric starter with belt or chain can be employed, and is operably connected to the cuff 18 of the compressor.

Although no sparking system is shown, it is possible to use either the jump spark or a make and break spark the spark plugs of this invention being placed optionally in either the stator of the exploder or the conduits from the exploder to the annular chamber of the turbine, or in the annular chamber of the turbine, or placed in all three places to be used respectively, or optionally, as found most efficient for varying loads or speeds.

The conduits 11 are elongated in transverse section so that the explosive fluid is directed to the greatest area possible at the inlet end of the turbine.

From the foregoing description taken in connection with the drawings, it is evident that the rotor of the compressor will operate about the crank shaft so as to impart the desired reciprocatory movement to the respective pistons and so that the charge of one member will be drawn inwardly during the explosion and exhausting of the opposite cylinder while the remaining cylinders are compressing, so that where two sets of cylinders are employed as herein illustrated, a continuous flow is delivered between the stator and rotor of the turbine at four equally distant points so that the explosive charge not only acts impulsively but also expansively.

The stator of the exploder is water cooled and is provided with a jacket 42 while the rotating part, as herein set forth, is air cooled.

From the foregoing description the operation of the present apparatus is apparent, and briefly stated it is as follows: The rotor of the compressor is started in any desired manner, electrically, pneumatically or manually. During this action each one of the pistons is so operated to cause the cylinders to consecutively receive the charge on the inward movement of its respective piston, the charge being compressed at the point between the extreme end of the intake port and the exhaust port. As the explosion takes place at the point opposite the exhaust port the full impact and expansive force of the charge is directed through the exhaust port into the turbine. The compressing action upon the gas takes place when the outer end of the cylinder is opposite the solid portion of the stator, so that it is completely compressed and exploded just before the cylinder moves adjacent the ex-

haust port and as the exhaust port of the stator is diametrically opposite to the intake portion of the stator, a balanced engine is produced.

5 What I claim as new is:

1. The combination with a turbine having a rotor and a stator, of mechanism for supplying an exploded expansible fluid thereto, including a stator, a rotor, fluid 10 conducting means between the stator and the space between the rotor and stator of the turbine, means for supplying the charge to the rotor of the supplying mechanism, said rotor of the exploder including a member 15 having a plurality of radially disposed cylinders, a piston mounted in each cylinder, a relatively fixed crank shaft connected to the pistons, means for operably connecting the rotor of the supplying mechanism to the rotor 20 of the turbine whereby the rotor of the supplying mechanism is operated by the turbine, manually controlled means for oscillating the crank shaft to vary the compression of the cylinders, and a variable transmission mechanism between the two rotors 25 whereby the speed of the rotor supplying mechanism is changed relative to that of the turbine.
2. In combination with an expansible fluid 30 turbine having a stator and a rotor mounted therein providing a circumferential space, of means for supplying a compressed fluid to said space and for itself in turn being operated by the rotor of the turbine, including an outer casing having a plurality 35

of diametrically disposed intake and exhaust ports, a rotating member mounted therein having a plurality of radial cylinders, the outer ends of said cylinders being closed by the casing, a plurality of pistons 40 one mounted in each cylinder, an adjustable crank shaft operably connected to all of said pistons, manually controlled means for adjusting the crank shaft to regulate the active positions of the pistons, and variable transmission means between the rotor of the turbine and the revolving member of the supplying mechanism.

3. The combination with an expansible fluid turbine having a rotor and a stator, of 50 means for supplying the expansive fluid to the turbine including a rotor having two oppositely disposed exhaust ports leading from the periphery thereof at diametrically opposite points, one charge intake port being 55 aligned with the diametrically opposite exhaust port, a rotor mounted within said stator and provided with four pairs of open-ended cylinders disposed 90° to each other, the inner periphery of the stator closing the 60 outer ends of the cylinders, transmission means operably connected between the rotor of the turbine and the rotor of the supplying means whereby the latter is driven from the former, a plurality of pistons one mounted in each cylinder, and an adjustable crank shaft operably connected to all pistons.

In testimony whereof I affix my signature.

GEORGE GORDON BOWER.
